US0D1042971S

(12) **United States Design Patent** (10) **Patent No.:** **US D1,042,971 S**
(45) **Date of Patent:** **** Sep. 17, 2024**

(54) **HANDHELD SPRAYER**

(71) Applicant: **Je Matadi, Inc.**, Stafford, TX (US)

(72) Inventor: **Pershant Mehta**, Stafford, TX (US)

(73) Assignee: **Je Matadi, Inc.**, Stafford, TX (US)

(**) Term: **15 Years**

(21) Appl. No.: **29/841,147**

(22) Filed: **Jun. 3, 2022**

(51) **LOC (14) Cl.** **28-03**

(52) **U.S. Cl.**

(57) **CLAIM**

The ornamental design for a handheld sprayer, as shown and described.

DESCRIPTION

FIG. 1 is a left, front, top perspective view of the handheld sprayer;

FIG. 2 is a right, rear, top perspective view of the handheld sprayer;

FIG. 3 is a left elevation view of the handheld sprayer;

FIG. 4 is a right elevation view of the handheld sprayer;

FIG. 5 is a back elevation view of the handheld sprayer;

FIG. 6 is a front elevation view of the handheld sprayer;

FIG. 7 is a top view of the handheld sprayer; and,

FIG. 8 is a bottom view of the handheld sprayer.

The shade lines in the Figures show contour and not surface ornamentation.

The broken lines show portions of the handheld sprayer that form no part of the claimed design.

1 Claim, 8 Drawing Sheets
